dinal seams, the new blouse structure can be readily and properly adjusted to the individual size of the wearer, and various effects may be obtained with respect to the appearance and fitting (snug or draped) of the blouse on the wearer.

It is well understood that the front section of the blouse may be also tucked under the skirt, if so desired.

Lower edge 20 and tie means 24, 25 attached thereto are preferably positioned along the waist line of the wearer.

Due to the fact that the blouse is open directly under the sleeve and next to the armpit, no perspiration will affect the blouse material since always air circulation will be maintained.

It is further to be kept in mind that the blouse structure can be manufactured with long or short sleeves or without any sleeves, and that no alterations or changes of the seams are required to fit various sizes of persons wearing such garment structure.

Although the above improvements relating to garment and in particular to blouse structures have been described with respect to a certain embodiment of the invention, it is not desired to be limited to such details since changes and modifications in the form, arrangements, proportions and sizes thereof may well be made without departing from the spirit and scope of the invention in its broadest aspect.

Having thus described the invention, what is claimed as new and desired to be secured by Letters Patent is:

1. In a blouse or like garment having a front section and a rear section connected together by seams extending along the shoulders of said gar-

ment, and having sleeves extending from said shoulder seams; said rear section and said front section being each provided with free side edges, substantially horizontally directed seams connecting the respecting upper ends of said side edges of said front section and the respective upper ends of said side edges of said rear section adjacent the armpit of said sleeves, said horizontally directed seams being so disposed that said front section is arranged with respect to said rear section in overlapping position, the upper end of each side edge of said front section being spaced from the upper end of each side edge of said rear section, and tie means connected to the respective lower ends of the side edges of said front section and adapted to extend above said rear section whereby said front section is retained in position on said rear section.

2. In a blouse or garment having a front section and a rear section and connected together by seams extending along the shoulders of the garment; said rear section and said front section being provided with side edges, respectively, substantially horizontally directed fastening means connecting the respective upper ends only of said side edges with one another, whereby the remainders of the side edges of said front section loosely overlie the side edges of said rear section, and tie means fixed adjacent the lower ends of said side edges of said front section, whereby said front section may be adjusted relatively to said rear section and in overlapping relation thereto and retained in position with said lower ends of said side edges on said rear section.
